ANDREW S. T. MERRIMAN, OF CHICAGO, ILLINOIS.

Letters Patent No. 99,218, dated January 25, 1870.

IMPROVED STONE-PLANING MACHINE.

The Schedule referred to in these Letters Patent and making part of the same.

To all whom it may concern:

Be it known that I, ANDREW S. T. MERRIMAN, of Chicago, in the county of Cook, and State of Illinois, have invented a new and useful improved Stone-Planing Machine; and I do hereby declare the following to be a full, clear, and exact description thereof, which will enable others skilled in the art to which my invention appertains, to make and use the same, reference being had to the accompanying drawings, forming part of this specification, in which the figure is a transverse vertical section of my improved stone-planing machine.

My invention has for its object to more effectually plane the surfaces of stones employed for pavements and building-purposes.

It consists, first, in a stone-planing machine, adapted to plane the top and one or both edges of a stone, either plain or otherwise, simultaneously.

It further consists in the construction of the box for holding the tools which plane the upper surface of a stone, whereby said surface can be planed to its extreme edge while the latter is being cut.

In the accompanying drawings—

A is the bed or frame of the planer, to the two opposite sides of which are bolted the uprights B, which are connected together by the top plate or beam C.

D is the plate or table upon which the stone is held while being cut, and is adapted to be moved upon the guides E E longitudinally of the frame A, by means of the screw-shaft F, working through a nut, G, upon the under surface of the table, and having its bearings in the frame A.

Motion is communicated to the screw for moving the table, through the band-wheel H, affixed to the end of said screw, or by any other suitable means.

I is a cross-bar or frame for carrying the tool-boxes.

It is suspended at each end from the top plate C, by means of the vertical screws J, having bevelled pinions K upon their upper ends, which engage with corresponding pinions upon the longitudinal shaft L, upon the top plate.

By operating the shaft L, the cross-bar is raised or lowered, being guided in its movements by projections upon its back, working in the vertical slots of the standards B.

M are hand-crank upon the ends of the shaft L, by which said shaft is operated.

N N are the tool-boxes, carrying the side-cutters O.

They are each composed of a rectangular box, whose side pieces P are fitted upon screw-rods Q Q, which extend through the ends of the cross-bar I, and parallel with the same. By operating these screw-rods, the two boxes are moved to or from each other.

The front plates R of the tool-boxes carry, near their lower ends, the cutters O, and are moved verti-

cally upon the side pieces P by means of the hand-screws T, as shown.

The cutters O are arranged for adjustment upon the proximate sides of the tool-boxes N, and are either straight, or so formed as to cut mouldings, rebates, &c., upon the edges of the stone.

U is the tool-box for the cutters which plane the upper surface of a stone.

It is suspended upon the longitudinal screw-rod V, and is, by said screw-rod, adjusted laterally between the tool-boxes N N.

The tool-box U is composed of a back plate, W, through which the screw-rod V passes, and a front plate, X, to which the tools or cutters Y are attached, in the position shown in the drawings.

The front plate X is hinged, at Z, to the face of the back plate, and its side bars or plates A' fit over the side of said back plate.

By this construction, the cutters Y are permitted to be moved laterally over the stone to the extreme edge of the same, while the side-cutters O are in operation.

This could not be accomplished if the back plate W of the tool-box U were provided with side bars, and the front plate X adapted to fit between them, for the reason that said side bars would project so far laterally as to prevent the cutters from being placed at the extreme edges of the tool-box, and would, therefore, leave a space between them and the side-cutters O, which space would remain upon the stone unplaned.

The operation is as follows:

A stone to be planed or cut is placed upon the table D, being retained in place by means of pointed screws working through four studs, B', which are adapted to fit in holes formed in the table. When the stone has been so secured, the tool-box U is moved, by means of the rod V, to one side of the frame, and adjusted so that its cutters shall make the requisite cut, by operating the cross-bar I, as before mentioned.

The stone is then fed longitudinally of the machine, against the cutters, by operating the table, through the medium of the screw-shaft F, thus cutting a smooth surface, of the width of all the cutters. The stone is then moved back to the opposite side of the machine, and the cutters adjusted laterally of the cross-bar I, to form a new cut, when the stone is again fed forward. This operation is repeated until the upper surface of the stone is completely planed.

It has been remarked that the front plate X of the tool-box U is hinged to the back plate. This arrangement is to permit the cutters to swing outward from the back plate, whenever they encounter chips or projections upon the stone, during its backward movement. Without this provision, the chips of stone coming against the backs of the cutters would be liable to break and injure them, whereas, if they swing

outward, they pass readily over such obstructions, without injury.

One or both edges of the stone are cut of the required form, by adjusting the side-cutters O longitudinally and vertically of the cross-bar I, as previously described, so that the stone shall be fed against them, in its passage through the machine.

When the cutters Y become dulled, they may be removed, for sharpening, by unhinging the plate X from the back plate W.

Having thus described my invention,

What I claim as new, and desire to secure by Letters Patent, is—

1. In a stone-planing machine, the top and side-cutters, constructed and combined to cut the top and one or more edges of a stone simultaneously, substantially as described.

2. The tool-box U, having the side bars A' of the hinged front plate X, adapted to enclose the sides of the back plate W, substantially as described, for the purpose specified.

ANDREWS T. MERRIMAN.
